Inventor:

UNITED STATES PATENT OFFICE.

CORNELIA M. POST, OF PHILADELPHIA, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR LINOLEUM, OIL-CLOTH, OR FLOOR-COVERING.

47,341.

Specification for Design.

Patented May 11, 1915.

Application filed March 25, 1915. Serial No. 17,061. Term of patent 7 years.

To all whom it may concern:

Be it known that I, CORNELIA M. Post, a citizen of the United States, and a resident of Philadelphia, in the county of Philadelphia and State of Pennsylvania, have invented a new, original, and ornamental Design for Linoleum, Oil-Cloth, or Floor-Covering, of which the following is a full, clear, and exact description, reference being had to the accompanying drawing, forming part of this specification.

The figure is a plan view of a piece of linoleum embodying my design.

I claim:

The ornamental design for linoleum, oil cloth or floor covering as shown.

CORNELIA M. POST.
